UNITED STATES PATENT OFFICE

154,947

DESIGN FOR A CRUISING LIGHT

Shelton H. Moore and Robert Freedman,
Baltimore, Md.

Application February 12, 1948, Serial No. 144,434

Term of patent 3½ years

(Cl. D48—32)

To all whom it may concern:

Be it known that we, Shelton H. Moore, a citizen of the United States, residing in Baltimore city, in the State of Maryland, and Robert Freedman, a citizen of the United States, residing in Baltimore city, in the State of Maryland, have invented a new, original, and ornamental Design for a Cruising Light, of which the following is a specification, reference being had to the accompanying drawing, forming part thereof, in which:

Figure 1 is a perspective view of a cruising light, showing our new design.

Figure 2 is a front view thereof; and
Figure 3 is a rear view thereof.

We claim:

The ornamental design for a cruising light, substantially as shown.

SHELTON H. MOORE.
ROBERT FREEDMAN.
